COVERED SLIDE BUCKLE

Daniel I. Reiter, New York, N. Y.

Application May 23, 1940, Serial No. 336,688

9 Claims. (Cl. 24—77)

This invention relates to slide buckles of the general type shown in my prior Patents Nos. 1,857,973 and 2,177,119.

In such buckles, a main frame slidably carries an auxiliary frame or slide which in turn optionally carries an element of a separable snap fastener. Cooperating detent means may also be provided on the frames to prevent accidental disturbance of the relative adjustment thereof.

The present invention contemplates the extension of the field of usefulness of such slide buckles to many types of garments, belts, and straps to which my prior patented buckles could not heretofore be economically applied.

This invention further contemplates the provision of a covered and hence a protected and ornamental main frame which may be formed in a number of different ways and made of a number of different materials, and provided with suitable means for slidably and adjustably supporting the auxiliary frame or slide.

This invention further contemplates the provision of an adjustable and self-locking buckle having an ornamental sheet metal or wire frame covered with leather or the like, or textile or the like fabric, whereby a comparatively inexpensive adjustable slide buckle is produced capable of many decorative and useful applications in garments of various kinds.

The invention further contemplates the provision of an adjustable and inexpensive slide buckle made at least in part of inexpensive sheet metal such as iron or steel and covered with leather, fabric or the like, and having the adjustable slide and detent features above-mentioned whereby the buckle is adapted for use in a large variety of garments and straps and belts therefor.

The various objects of the invention will be clear from the description which follows and from the drawings, in which,

Fig. 1 is a front view of a covered slide buckle embodying my invention.

Fig. 2 is a horizontal section thereof taken on the line 2—2 of Fig. 1 and showing the belts or straps in place in the buckle.

Fig. 3 is a fragmentary vertical section of the same.

Fig. 4 is a front view similar to Fig. 1 of a modified form of the main frame of the buckle.

Fig. 5 is a similar view of a modified form of the invention wherein a covered wire frame is provided for directly supporting the buckle slide member.

Fig. 6 is a front view of a covered frame made

of sheet metal and on the arms of which a slide may be secured.

Fig. 7 is a side view of the same.

Fig. 8 is a front view of a developed strip of sheet metal from which the frame of Fig. 6 may be bent up.

Fig. 9 is a front view of a buckle provided with a frame similar to the frame of Fig. 6, except that the frame is formed of wire parts soldered together instead of a cut-out strip of sheet metal.

Fig. 10 is a vertical section, similar to Fig. 3, of a modified form of the main frame, wherein the slide support is made in the form of a cross piece integral with the inner portion of the main frame.

Fig. 11 is a similar section of another modified form of the main frame, wherein the slide support is integral with the outer part of the main frame.

Fig. 12 is a similar section of another modified form of the main frame combining the inner frame part of Fig. 10 with the outer frame part of Fig. 11 to provide two similar cross pieces for supporting the slide.

Fig. 13 is a similar section of another modified form of the frame wherein a strip of U-shaped cross-section is used and the inner frame member omitted.

Fig. 13a is a cross-section of the frame member of Fig. 13.

Fig. 14 is a section of another modified form of the frame made of a strip of sheet metal doubled on itself.

Fig. 14a is a cross-section of the frame member of Fig. 14.

Fig. 15 is a vertical fragmentary section of Fig. 9 showing one form of the cooperating detent means on the main frame and on the slide.

Fig. 16 is a similar view showing a modified form of the bent over arms of the slide.

In the practical embodiment of the invention which I have shown by way of example and referring particularly to Figs. 1, 2 and 3, the main frame designated generally by the numeral 10 comprises an annular outer frame member 11 of U-shaped cross-section and made of comparatively thin and cheap metal such as iron or steel, and the inner annular frame member 12 of similar material, also of U-shaped cross-section and telescoped into the member 11. A sheet of suitable fabric, leather or imitation leather or the like material 13, covers the outer face of the member 11 and its side edges and is tucked between the adjacent cooperating legs of the frame members 11 and 12 and held in stretched condition thereby. When said members are telescoped together, the 55

peripheral edges of the covering 13 are clamped tautly in place. A central opening as 14 is provided in the main frame and within the annular members thereof. Said opening is partly closed by the cross piece 15 which is suitably secured to the frame member 12 as by the rivets or the like fastening means 16. The frame cross-piece 15 is preferably of greater length than that of the opening 14 and of lesser width whereby the remaining parts of the opening 14 not obstructed by the cross piece, constitute a pair of spaced slots 17 and 18 through which the belt or strap 19 is passed to overlie the cross piece and the slide 20 carried thereby and to conceal them from view when the buckle is in use.

It will be understood that the cross piece 15 may be made of material considerably thicker than that of the frame members 11 and 12 in order to resist the rather severe stresses put thereupon. In said cross piece are provided the spaced slots 21 and 22 having parallel inner edges at right angles to the outer edges 23 and 24 of the cross piece and constituting guides controlling the movement of the slide 20. A third slot 25 between the slots 21 and 22 is made in the cross piece to receive the end of the stud 26 (Fig. 2) when said stud is engaged by the resilient socket 27 carried by the slide. Those portions 28 and 29 of the cross piece between the slots 25 and 21, and 25 and 22 comprise the arms which support the slide for transverse movement. On such movement, the end edges of the slide may be projected into the slots 17 and 18 to engage the strap 19 and to hold said strap in its adjusted position to the buckle. The edge portions of the slide 20 are doubled back to a position parallel to the body part 30 to form the arms 31 of the slide. Reduced connecting parts between the arms 31 and the body 30 pass through the slots 21 and 22 and slide on the edges of said slots. The body part 30 is provided with a pair of spaced slots 33a through which the attaching prongs 33 of the cylindrical socket member 27 are passed and turned over to hold the socket member in place. Arranged between the body part 30 of the slide and the overhanging flange of the socket member is the split resilient ring 32 which inwardly overhangs the edge of a circular opening 35 in the body part 30. The resilient socket thus formed may readily be engaged by the stud 26 suitably secured to another strap or belt part 34 of a garment or the like, whereby the strap parts may be detachably secured together. When the fastener is assembled, the head of the stud enters the opening 35 of the slide and the opening 25 of the cross piece 15.

It will be noted that the slide 20 is adjustable along the cross piece and relatively to the frame 10 from its extreme position at the left, as shown in Fig. 1, to an extreme position at the right, and may also be adjusted into intermediate positions. When at the right, the right-hand end of the slide is projected into the slot 18. Since the prongs 36 are provided preferably at both ends of the arms 31 and the body part 30, said prongs engage and grip that part of the strap which passes through the slot 18. It will also be noted that the prongs may take a number of different forms or may be omitted as will later appear.

Detent means are optionally provided for maintaining the slide 20 in any position which it may be set relatively to the cross piece 15. Said means may take the form of a projection 37 made in

the arm 31 and extending in a direction to engage and rest between corresponding projections as 38 made in the cross piece 15 and extending toward the projection 37. Movement of the slide relatively to the frame and cross piece is resisted by the obstructing action of the projections 38 to movement of the projection 37 therewith. When a number of projections 38 are arranged in spaced relation in the direction of the movement of the slide 20, then the slide may be adjusted to a position wherein the projection 37 is between a selected pair of projections 38 and is thereby self-held in such position. To cooperate with the prongs 36 on the slide 20 to hold the part 19 in its adjusted position in the slots 17 and 18, an additional prong or projection 39 may extend inwardly of each of the inner edges of the frame member 11 and into the slots.

It will be understood that the main frame member 10 may take a variety of different forms, 20 the particular form shown in Fig. 1 being octagonal. As shown in Fig. 4, however, the main frame 40 is of substantially square shape provided with an opening 41 therein of rectangular shape and divided by the cross piece 15 into a pair of spaced edge slots 42 and 43. The main frame 40 may, similarly to the main frame 10, consist of two annular telescoped parts 11a and 12a each of U-shaped cross-section adapted to hold the covering 44 thereof in place. The slide 20 being constructed similarly to the slide of Fig. 1, no further description thereof is deemed necessary.

In either of the forms of the buckle thus far explained, it will be understood that the cross piece 15, instead of being made of a separate piece secured to one of the frame members, may be made integral with either or both of the main frame members as is shown in Figs. 10, 11 and 12. In Fig. 10, the cross piece 45 is made integral with the inner frame member 46 and is provided with slots 21a, 22a in the same manner as the cross piece 15 is provided with the slots 21, 22. Preferably, the material of the inner frame member in this case is made somewhat thicker than that of the outer frame member 11 so that the cross piece 45 is given sufficient strength to resist the stresses put thereupon.

As shown in Fig. 11, the cross piece 47 is made integral with the outer frame member 48, and as shown in Fig. 12, both cross pieces 45 and 47 and both frame members 46 and 48 are used, whereby the material of both frame members may be comparatively thin and of equal thickness.

As has been hereinbefore mentioned, the buckle frame, while covered in all the forms illustrated, may be made of one or more parts and with or without a cross piece, but with a slide and belt slots, and the slide may be provided with prongs or teeth or other forms of belt-engaging edges.

Referring now to Fig. 5, I have there shown the main frame member 50 formed of a single piece of wire bent into generally H-shaped form. The ends 51, 52 of the length brought together at about the middle of the side bar 53 are there soldered, welded, brazed, or otherwise suitably secured together. The length of wire forming the frame is so bent as to provide parallel spaced side bars 53 and 54 of substantially equal length, a pair of shorter aligned belt-slot-defining bars 55, 56 parallel to and spaced sufficiently from the side bar 53 to provide the belt-receiving slot 57; a second pair of belt-slot-defining bars 58, 59 similarly parallel to and spaced from the side bar 54 and defining the belt-receiving slot 60,

end bars as 61, 62 integral with and joining the outer ends of the bars 53, 55 and 56, similar end bars joining the bars 54, 58 and 59, and the pair of parallel slide supporting bars 63, 64 joining the corresponding ends of the pairs of belt-slot-defining bars. A tubular sheath or cover 65 comprising a strip of fabric, leather or the like is wrapped around the wire with the peripheral edges thereof secured together as by means of the stitching 66. A similar sheath or cover similarly made encloses the other side of the main frame including the various bars with the exception of the slide supporting bars 63, 64.

The slide 20a is mounted for sliding movement on the bars 63, 64 and carries a resilient socket 27 as hereinbefore explained in connection with Figs. 2 and 3.

The prongs on the ends of the arms 31a and on the body portion 30a of the slide may be greatly varied in shape and size or omitted, but as shown in Fig. 5 are of the single tooth type 67. The detent 68, 69 provided for movably maintaining the slide 20a in its adjusted position on the slide bars 63, 64 is shown in Fig. 5 in the form of a projection 68 on the reduced portion of the slide adapted to cooperate with recesses 69 in the outer part of the slide bar 63. It will be understood, however, that the detent may take various forms, as shown by the detent 31, 38 of Fig. 3, and that the arms 31a may also take various forms.

As shown in Fig. 15, a series of spaced notches as 79 are formed in the slide bar 63a and the projection 71 pressed inwardly from the material of the arm 31b of the slide to enter the recesses 70. Said arm 31b terminates in the serrated edge 36 in the form shown. In the form of Fig. 16, the arm 72 of the slide is bent and encircles the cross bar 63b instead of being made parallel to the body portion 30c of the slide. In Fig. 6, the body part 30d of the slide is made longer than the arms 31d thereof and the prongs have been omitted from the ends of the arms and body portion. The straight end edge 73 however cooperates with the frame of the buckle to grip a belt therebetween. In Fig. 9, the arms 31e are made longer than the body portion and terminate in end edges 74 intended to enter the belt slots and grip the belt. It is intended that any of the various forms of the detent means or prongs may be used on the slide of any of the frames, but to reduce the number of figures of the drawings, the different slides have been shown only in connection with the frames of Figs. 5, 6, 9 and 16.

In the form of the invention shown in Figs. 6, 7 and 8, the frame 75 is formed from a strip of comparatively thin sheet metal, cut or stamped in the shape of the straight strip shown in Fig. 8, having a portion of uniform width and a pair of integral loops 76, 77 outstanding therefrom at the proper spaced intervals. The strip is bent on the dotted lines 78 of Fig. 8 to bring the ends thereof together at the side bar 79 of the frame where said ends are soldered, welded, brazed or otherwise suitably secured together. The side bars 79, 80 and the end bars 81, 82 of the frame 75 are covered by the sheath or covering 83 similar to the sheath 65, but preferably the loops 76, 77 are not covered. A slide 20d similar to the slides hereinbefore described, is mounted for movement on the slide supporting bars 84, 85 at the inner parts of the loops, said slide supporting bars being provided, if desired, with projections

or indents forming detent means similar to those hereinbefore described.

In the form of the invention shown in Fig. 9, the main frame 86 is preferably made in the form of a rectangle of a single piece of wire with the ends suitably secured together as at 87. Separate U-shaped loops as 88, 89 are soldered, welded, brazed or otherwise suitably secured to the respective end bars 90, 91 of the frame thereby providing slide supporting bars 92, 93 for the support of the slide 20e. The detent 10a, 11a on the slide is similar to the detent 10, 11 and has been sufficiently described hereinbefore and no further description thereof is therefore deemed necessary. However, the arms 31e of the slide are here shown as terminating in straight edges instead of serrated edges. The covering 94 is also made preferably in the form of a strip or sheath similar to the sheath 65 of Fig. 5 and covers the frame 86 but not the loops 88, 89.

In Figs. 13 to 14, I have shown other constructions of covered buckle frames which may each be made of a single piece of sheet metal and provided with a slide-carrying cross piece, but in which the covering need not be stitched to the frame nor made in the form of a sheath, nor held in place by telescoping frame members as in the forms hereinbefore described. Instead, the parts themselves of the one-piece frames are utilized to hold both the covering and the cross piece. As shown in Figs. 13 and 13a, the annular frame 95 of any desired polygonal outline is of a single piece of channel stock, or U-shaped in cross-section having a web 96 and legs 97, 98, and is bent into the desired configuration with the ends of the strip of stock secured together at a side of the frame. The cross piece 15c extends across the central opening of the annular frame as has been fully explained in connection with the crosspieces 15 of Figs. 1 and 4. However, the ends 99 of the cross piece are bent and inserted between the legs 97, 98 which are clamped tightly together with the cover sheet 100 covering the outer face of the web 96 and both faces of the legs. The free edges of the legs 97, 98 are also clamped together beyond the bent ends 99 of the cross piece and hold the peripheral edge portions of the cover 100 in place without the aid of any other holding means. It will be understood that the thickness of the metal of the frame 95 is exaggerated in the drawings for the sake of clarity.

In Figs. 14 and 14a, a flat sheet of metal is stamped out into annular form having a central opening. The inner part 101 of the sheet surrounding the opening is preferably unmutilated but the remainder 102 of the sheet is provided with suitable corner cut-outs to permit it to be doubled back on the face 101 in a manner which is well understood in the working of sheet material and hence need not be illustrated. The cross piece 15d is inserted between the doubled together parts 101 and 102 of the frame with the peripheral edge parts of the covering 103 tucked therebetween. Said edge parts as well as the ends of the cross piece are clamped in place by pressing the parts 101 and 102 firmly together without the necessity for the use of stitching, or any other additional means. In this form of the frame, the parts 101 and 102 are parallel and arranged in face to face relation, while all parts of the frame are covered except the cross piece.

It will be understood that in all of the forms of the buckle herein described, the main frame is

completely or partially covered by suitable flexible material which may be colored or ornamented as desired to form an ornamental buckle adapted for use in articles of so-called "dressy" wear as well as for work garments, and providing a wide range of possible ornamentation by the use thereon of color, or impressing or stamping processes, or the use of colored and shaped materials of various types.

10 It will also be understood that the main frames have their exposed and visible portions ornamented by the covering material and may be made in a great variety of different forms and of one-piece or several pieces as has been hereinbefore 15 illustrated. In any case, however, it will be seen that I have provided an ornamental buckle which is self retained in its adjusted position and in which the adjustment cannot be accidentally disturbed yet which is efficient as well as ornamental 20 and well adapted to meet the severe requirements of practical use.

From the above, it will also be understood that various changes may be made from the specific forms of the buckle herein shown, without departing from the spirit and scope of the invention and coming within the range of equivalents afforded by the appended claims.

I claim:

1. In an adjustable slide buckle, a metallic frame having end members, and having side members each provided with a substantially straight inner edge parallel to and spaced from the corresponding inner edge of the other side member, a slide-supporting member on the frame having spaced parallel edges at right angles to and arranged between said inner edges of the side members, and having outer edges substantially parallel to and spaced inwardly from the adjacent inner edge of the side members to define a pair of spaced belt-receiving slots in the frame, a cover of a sheet of flexible non-metallic material stretched over the side members of the frame, means securing said cover in place, a slide member having arms passing around the above-mentioned edges of the slide-supporting member and movable in the direction of said edges toward and from the inner edges of the side members, a snap fastener element carried by the slide member and cooperating detent means on the slide member and the slide-supporting member for resisting movement of the slide member out of the adjusted position thereof.

2. In an adjustable slide buckle, a frame having an outer face and an inner face, a sheet of flexible non-metallic material covering at least the outer face of the frame and stretched tightly thereover, parallel slide-supporting arms on the frame, a slide supported by said arms and carrying a snap fastener element and cooperating detent means on the arms and the slide.

3. In an adjustable slide buckle, a first sheet metal annular frame member of U-shaped cross-section, a flexible non-metallic cover for said member, a second annular metallic frame member of U-shaped cross-section telescoped into the first frame member with the peripheral edge of the cover held therebetween, said frame members having registering central openings therein, a slide-supporting member extending across the opening and defining a pair of belt-receiving slots,

and a slide supported by the slide-supporting member and adapted to engage a belt passed through the slots.

4. In an adjustable slide buckle, a rectangular wire frame, a pair of similar U-shaped loops secured to the narrower edges of said frame and extending toward each other and thereby providing a pair of adjacent slide-supporting arms, said U-shaped members being of less width and less length than the width and length of the frame, a flexible non-metallic cover mounted on the frame and a belt-engaging slide slidably mounted on the arms.

5. In an adjustable slide buckle, an annular metallic frame having side bars and end bars, an ornamental flexible non-metallic cover stretched on the frame, means forming part of the frame for holding the peripheral edges of the cover in place, a slotted slide-supporting cross piece extending between the end bars, and a belt-engaging slide slidably mounted on the cross piece and having arms bent through the slots of the cross piece.

6. In an adjustable slide buckle, a metal frame having side bars and end bars and having a loop extending inwardly from each of the end bars, each of said loops having a slide-supporting arm parallel to the corresponding arm of the other loop and of less length than that of the end bars, and a flexible covering sheet enclosing the side bars and the end bars of the frame.

7. In an adjustable slide buckle, a metal frame of greater width of material than the thickness of said material, said frame having side bars and end bars, a sheet of non-metallic material covering the end bars and side bars, means for securing the peripheral edges of said sheet in place, means extending between the end bars for slidably supporting a slide, and a belt-engaging slide slidably mounted on said means.

8. In a slide buckle, a generally H-shaped metal frame provided with a pair of parallel slide supporting arms of less length than the width of said frame, a flexible moisture-resisting sheath for the remainder of said frame excepting the arms, a slide mounted on and for movement longitudinally of said arms, prongs on the slide, a socket carried by the slide and cooperating detent means on the slide and said arms for preventing accidental movement of the slide relatively to the frame.

9. In a slide buckle, a generally H-shaped metal frame comprising a pair of spaced side bars, an aligned pair of spaced shorter belt-slot-defining bars parallel to and spaced inwardly of each of the side bars, end bars joining the outer ends of the side bars and the belt-slot-defining bars, a pair of slide-supporting bars each integrally joining the inner ends of the corresponding bars of the pairs of belt-slot-defining bars and perpendicular thereto, the slide-supporting bars being parallel and bare, a tubular sheath of flexible material covering said bars except the slide-supporting bars, a slide mounted for movement longitudinally of said slide-supporting bars, a snap fastener element carried by the slide, and cooperating detent means on the slide and the slide-supporting arms for preventing accidental movement of the slide relatively to the frame.

DANIEL I. REITER.
